ABSTRACT

An electromagnetic circuit with a yoke and a movable armature in a channel of a coil, with one end of the armature pivoted against one end portion of the yoke and with the other free end of the armature forming a working airgap with the yoke. The yoke has a substantially flat shape with a notch or an aperture for the coil to nest in so that the coil channel and the armature are situated substantially at one side of the flat yoke and the working airgap is outside of the coil.

ELECTROMAGNETIC CIRCUIT

BACKGROUND OF THE INVENTION

The invention relates to the type of electromagnetic circuits that are particularly well suited for miniature relays with very small dimensions and preferably intended for mounting on printed circuits boards. The height of the relay measured from the board must be small, preferably corresponding to the height of a transistor which is less than 15 mm., for example 8 mm.

A primary object resides in providing a simple but effective novel electromagnetic circuit adaptable for miniature relays providing small dimensions and good operating characteristics.

A further object of the invention resides in providing a magnetic circuit having a flat planar yoke member with parallel end portions and at least one side portion adjoining the ends of the two end portions, a coil disposed adjacent the yoke side portion and between the yoke end portions with its axis parallel to the side portion and the center opening or channel through the coil disposed to one side of the flat planar configuration of the yoke, and a movable armature member extending completely through the coil with one of its ends pivoted against one of the yoke end portions and the other armature end extending beyond the end of the coil to a disposition adjacent a planar side face of the other end portion of the yoke for movement toward and away from the other yoke end portion, being so situated to provide a working airgap located outside of the coil.

Still another object, in conjunction with the previous object resides in providing the yoke with two spaced-apart side portions adjoining the two end portions to provide a planar flat box frame yoke structure within the central opening of which, a part of the coil is disposed and adjacent one of the flat planar yoke faces the armature is disposed.

A still further object resides in an electromagnetic circuit made in accord with either of the previous two objects and in combination with miniature relay contacts to provide a miniature relay with low-thickness profile suitable for printed circuit application.

Further novel features and other objects of this invention will become apparent from the following detailed description, discussion and the appended claims taken in conjunction with the accompanying drawings.

BRIEF DESCRIPTION OF DRAWINGS

A preferred structural embodiment of this invention is disclosed in the accompanying drawings, in which:

FIG. 1 is a top view of a part of the magnetic circuit according to the invention,

FIG. 2 is a corresponding view of another part of the circuit,

FIG. 3 is a sectional view of the assembled circuit,

FIG. 4 is another sectional view taken at a right angle to the view of FIG. 3,

FIG. 5 is an outer top view of the assembled circuit, and

FIG. 6 is an outer side view of the assembled circuit.

In the figures, reference numeral 1 designates the stationary ferromagnetic part or the yoke of the magnetic circuit. Reference numeral 2 designates the moving part or the armature.

Reference numeral 3 designates the bobbin of the magnetizing coil. The winding of the coil is connected to terminals 10.

In the illustrated embodiment, the electromagnetic circuit 1,2,3 is used in an electromagnetic relay, and hence it is provided with a number of contact spring groups, the springs 12 of which are connected to terminals 13.

As will be evident from FIG. 6, all terminal pins 10, 13 project from one side of the relay. The terminals 10, 13 are intended to be connected (e.g., by soldering) to different parts of a printed circuit board.

In assembling the device, the yoke 1 is inserted between projections 4 of the bobbin 3 and is turned towards the part 9 on the coil bobbin. The yoke 1 is pressed against the part 9 by

a clip 5 provided with two legs, and so designed that it presses the yoke 1 and the part 9 of the bobbin against each other with high pressure. There are two slots in the coil bobbin into which the legs of the clip 5 are inserted. The ends of said legs are going through the slots to the opposite side of the coil bobbin 3 and are bent as indicated by reference numeral 5a in FIG. 5, in order to keep the clip 5 in place. Preferably, the slots in the bobbin have a width which allows the bent portions of said legs to be inserted therein. In that case the clip 5 may be present before assembling. Upon assembling, the clip snaps into the locking position indicated in FIG. 4 where it clamps the stationary ferromagnetic part 1 against the portion 9 of the coil bobbin 3, and the bent portions 5a of the legs engage the bottom surface of the coil bobbin part which they penetrate.

One end of a leaf spring 6 is fixed to the armature 2 as shown in FIG. 4, for example by spot welding. The other end of said spring is bent from the armature as shown and engages the inner, upper surface of a longitudinal opening in the bobbin 3, for keeping the armature in its rest position shown in FIG. 4. In this position the narrow end of the armature 2 is in pivoting engagement with the adjacent edges of the yoke 1. The opposite broad end of the armature is kept at a distance from the opposite end of the yoke 1 for forming a working airgap 7 between said broad end of the armature and said end of the yoke.

As will be evident from the figures, the yoke is shaped as a substantially plain, preferably rectangular frame, enclosing the coil. At one short side of said frame one of the ends of the said armature is pivoted and at the opposite short side of the frame, between said frame and the armature, the airgap 7 is formed. The two long sides of said frame which constitute connecting members between its two short sides, are located along the sides of the coil, in the longitudinal direction of the latter. Also the armature is substantially plain and has a width bigger than its thickness. The yoke and the armature are substantially parallel to each other and so arranged, that their adjacent surfaces substantially coincide when the armature is operated. One of the long sides of the yoke which is located at one of the sides of the coil can be dispensed with, in which case the whole magnetic flux has to pass through the other side.

Furthermore, one projection 8 is provided at the end of the bobbin, which is adjacent to the airgap. When the armature is in its rest position shown in FIG. 4, it rests against said projection 8. Said projection 8 and the inner bottom surface of the longitudinal opening in the coil bobbin 3, against which the armature 2 falls when the relay is demagnetized, has a damping effect on the movement of the armature and, therefore, prevents bouncing of the armature upon demagnetization of the relay.

Preferably, there are two contact spring groups 12, viz one at each side of the coil. Said contact spring groups are fastened to the long sides of the yoke 1 in any suitable way, e.g., by screwing or glueing.

There is one actuating rib 11 of insulating material fastened to each side of the broad end of the armature 2 and arranged to cooperate with the moving spring of said contact spring groups, so as to transmit movement from the armature to said springs.

It should be mentioned that with a test relay manufactured according to the foregoing description and which had a height of 7.5 mm. measured from a printed circuit board onto which it was mounted, a length of 28 mm. and a width of 20 mm., a traction force of approximately 200 grams was obtained when the working airgap was 0.3 mm. and the magnetizing coil was supplied with an electric power of 1.4 w. This surprisingly high traction force is obtained because of the extremely big area, around 15 mm.², in relation to the size of the relay, of those parts of the magnetic circuit (the armature and the yoke) which are passed by the magnetic flux generated by the current through the coil. Said area can be still more increased by making the relay broader. Because the armature 2 has a pole piece (the broad end of the armature) with an effective area

which is big in relation to the area of the armature and the yoke which are passed by the magnetic flux, said area of the yoke and armature can be fully utilized, i.e., magnetic saturation can be allowed to occur when the power dissipation in the coil has such a value that the normal allowable temperature rise in the coil is obtained.

In the test relay having the dimensions stated in the foregoing, the temperature rise in the coil was approximately 45° C. when the dissipation in the coil was 1.4 w. With this power dissipation in the coil, saturation in the magnetic circuit was obtained (where the area was 15 mm.²) when the airgap was 0.3 mm.

Preferably, those make contacts of the contact spring groups belonging to the relay, the closure of which is most delayed (close last) should be operated when the airgap has that size.

During the continued movement of the armature towards the yoke (further decreasing airgap) a very high saturation in the yoke and the armature can be allowed without any risk of interruption of the movement of the armature.

What we claim is:

1. An electromagnetic circuit adapted for use in a miniature relay comprising: a yoke; a magnetizing coil; and a movable, elongate armature disposed in and through the longitudinal center channel in said coil; said yoke being of substantially flat shape with two spaced-apart parallel end portions and at least one side portion adjoining an end of each of said end portions to provide said flat yoke shape with a space between said end portions; said coil being placed in the yoke space so that said coil channel and said armature, which is disposed through the coil channel, are situated substantially adjacent one side of said flat yoke with one end of said armature placed and pivoted against one end portion of said yoke and the other end of said armature projecting from said coil to a position adjacent said other end portion of said yoke to provide a working airgap between the other end of said armature and the other end of said yoke situated outside of said coil.

2. An electromagnetic circuit according to claim 1, characterized by the fact, that the part of the armature (2) which is 40

situated adjacent to the airgap (7) is broader than the rest of the armature and that the difference in width of said parts of the armature is so great, that magnetic saturation is obtained in the narrower part of the armature 2 which is located inside the coil.

3. An electromagnetic circuit according to claim 2, and forming a part of an electromagnetic relay, characterized by the fact that a relatively high magnetic saturation is obtained when the most delayed relay contacts are operated by the 10 movement of the armature, when the proper power for obtaining normal temperature rise (around 45° C.) is supplied to the coil.

4. An electromagnetic circuit as defined in claim 1, wherein 15 said coil includes a bobbin with retention projections on each end; said yoke, in assembly on said bobbin engages said projections; a clip cooperates with the end of said bobbin opposite the end where the working airgap is located and with one end portion of said yoke to press said pivoted end of said armature against the said bobbin projection on the end of said bobbin adjacent said clip.

5. An electromagnetic circuit according to claim 6, including 20 a coil bobbin characterized by the fact, that the end of the coil bobbin where the airgap 7 of the relay is located, is provided with a projection 8 against which the outer end of the armature 2 falls when the relay is released, and that said projection 8 together with the inner bottom surface of the longitudinal opening through the coil bobbin, against which the other parts of the armature fall when the relay is released, has a damping effect on the movement of the armature and prevent 30 bouncing of the armature.

6. An electromagnetic circuit as defined in claim 1, wherein 25 said yoke has only one elongate side portion and is shaped to provide a flat planar U-shaped member with the coil nested in the space between the end portions and against the side portion.

35 7. An electromagnetic circuit as defined in claim 1, wherein said yoke has two parallel side portions and is shaped like a flat planar box frame which encompasses the said space between the said yoke end portions.
